UNITED STATES PATENT OFFICE.

WILLIAM P. HUNT AND IRAH D. SPAULDING, OF BOSTON, MASSACHUSETTS,
ASSIGNORS TO WM. P. HUNT, OF SAME PLACE.

IMPROVED STEERING APPARATUS.

Specification forming part of Letters Patent No. 33,465, dated October 8, 1861.

To all whom it may concern:

Be it known that we, WILLIAM P. HUNT and IRAH D. SPAULDING, both of Boston, in the county of Suffolk and State of Massachusetts, have invented a new and useful Improvement in Ship-Steerers; and we do hereby declare that the following is a full and exact description thereof, reference being had to the accompanying drawings, and to the letters of reference marked thereon, making part of this specification.

The nature of our invention relates, first, to certain parts used to connect in an improved and self-equalizing or self-adjusting manner the traversing nut to the rudder-head; second, to an advantageous arrangement of springs to produce an elastic or yielding action of the frame of the steerer while turning or holding the rudder-head; third, to the construction of the hoop for the rudder-head and its connection to the rudder, all substantially as hereinafter represented and described, the said invention being an improvement on a steerer invented and patented A. D. 1855 by one Jesse Reed and upon others of its class.

With reference to the accompanying drawings, Figure 1 is a plan of a ship's steerer as improved by us. Fig. 2 is a side elevation of the same; Fig. 3, an elevation of one end. Fig. 4 is a sectional view. Fig. 5 represents several views illustrating the spherically-headed studs and the sliding socket-blocks, hereinafter described. Fig. 6 is a view of one end to illustrate an approved mode of securing the springs and also of securing the stands against any liability to be thrown out of their proper position. Fig. 7 is a plan of the rudder-head.

A is the rudder's upper end.

B is the rudder-head.

C is a screw furnished with two threads winding in opposite directions, one being a right-hand thread and the other a left-hand thread.

D D are nuts, one fitted to the right-hand thread and the other to the left-hand, and are thus made to move in opposite directions by the turning of the screw.

E are stands, in which are firmly fastened, with suitable screws and nuts and adjusting-keys, the guides F. The guides F firmly con-

nect the stands E and guide the nuts D D, which traverse back and forth between them by the action of the screw.

G is a hand-wheel by which to rotate the screw.

H H are spherically-headed studs. These studs are securely fitted to the nuts D and fastened by a suitable nut, the spherical head projecting downward. To this head are fitted the socket-blocks I, which are made in halves and connected by the straps. (Seen in Fig. 5.) These blocks are free to turn to a certain extent in all directions upon the spherical heads of studs H, so that when fitted into the grooves a in the rudder-head and made to play back and forth by its circular motion they shall in no case have a tendency to bind, however much the rudder-head or the nuts may be strained out of their proper position.

Without our improvement the studs are furnished with an unyielding square or rectangular head, which, being fitted to the groove in the rudder-head, is liable to bind and become immovable whenever by extra strain or otherwise the rudder or the nuts are either thrown out of their proper position. With our improvement this cannot occur, as the socket-blocks I readily adjust themselves to the sides of the groove, and this feature, too, renders it unnecessary to exercise so great care to adjust the screw and slides so as to make the axis of the rudder perpendicular to them, as is required when our improvement is not used. The load or labor upon the studs is not so severe in our case, because it is always presented at the center of the sphere, while in others it is liable to come upon the extreme end, while we at the same time make available for wear the full surface of the block's side.

The stands E, being rigidly connected as before named, are adjusted upon the timbers J between the brackets K, which are made fast and firm upon said timber or support. To each end of the stands E are fitted springs L, of rubber or other suitable material, and a suitable cap M is then interposed between them and the brackets K. Then a suitable screw N being fitted to the bracket is screwed up, forcing the caps M against the springs until they are compressed to the proper degree. This arrangement removes from the

steerer all objectionable rigidity and gives it an elastic or yielding action upon the nuts and rudder, while the screw is not required to move in its own bearings at all, except to rotate, but the stands, guides, and nuts all move together. Thus we obtain an apparatus which is at once more perfect and substantial than when springs are applied to the screws directly, and one of less cost.

The rudder-head B is made in halves and may be of cast-iron or other suitable material. This head is fitted to the upper end of the rudder, so as to leave a space for the strips of rubber P, and is also furnished with flanges and suitable bolts b, by means of which the rubber P may be suitably compressed upon the upper part of the rudder, and the head thereby confined to the rudder firmly and yet not rigidly, the elasticity of the rubber allowing a slight movement of the rudder within the head in all cases of severe strain. The usual lugs or projections to be let into the rudder may be cast within the head, but the corresponding grooves in the wood of the rudder should be enlarged in thickness, so as to allow the described action of the rubber before the iron and wood come into contact. The studs H may be made of wrought-iron or steel or other suitable material.

The general operation will be readily comprehended by reference to the drawings. The hand-wheel being rotated in one direction gives motion to screw C, which causes one half-nut to move in one direction and the other in an opposite one, thus causing the rudder-head to be turned in a direction corresponding to that of the hand-wheel's motion. The rudder-head thus receiving a circular movement, makes it necessary that the blocks I, which necessarily move parallel to slides F, should slip freely back and forth in the grooves a in the rudder-head, which they freely do under all reasonable conditions, as above described. When the hand-wheel is turned in the opposite direction, each half-nut is reversed in its movement and the rudder is

turned in the opposite direction. When any sudden torsional strain occurs upon the rudder during these operations, the springs L at once yield to a certain extent, allowing the whole screw-frame composed of stands E and the slides F to yield in the direction of the strain, and at the same moment the head B is allowed to yield slightly upon the rudder or the rudder within the head, and thus by the action of springs L and rubber P the various parts are protected from damage by the suddenness of the strains to which the rudder is subjected, while the universal stud H prevents any undue friction or binding in the grooves a and the steerer is rendered much more safe from damage and easily operated than without our improvements.

Thus having described the construction and operation of our improvements, what we claim as our invention, and desire to secure by Letters Patent, is as follows:

1. Forming the connection between the traversing nut D and the rudder-head by means of the spherically-headed studs H and the sliding socket-blocks I or in any combination of parts substantially equivalent to a universal joint, the said studs and blocks being constructed and arranged to operate substantially in the manner and for the purposes herein set forth.

2. The arrangement of the springs L with reference to and in combination with the stands E, said stands being rigidly connected to each other and supporting the screw, substantially as described.

3. Clamping the elastic medium P within the rudder-head, said head being constructed substantially as described, for the purpose set forth.

In testimony whereof we have hereunto set our hands.

WM. P. HUNT.
IRAH D. SPAULDING.
